ATTORNEY

UNITED STATES PATENT OFFICE.

PAUL BATEMAN, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CARRY-IRON.

1,078,243.

Specification of Letters Patent. Patented Nov. 11, 1913.

Application filed December 26, 1912. Serial No. 738,695.

To all whom it may concern:

Be it known that I, PAUL BATEMAN, residing at St. Louis, Missouri, and being a citizen of the United States, have invented 5 certain new and useful Improvements in Carry-Irons, (Case A,) of which the following is a full, clear, and exact description, such as will enable others skilled in the art to which it appertains to make and to use 10 the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a front elevational view of a coupling support 20 showing the coupler in section and showing in dot and dash lines the carry iron in dropped position. Fig. 2 is a plan view of the underside of the device shown in Fig. 2, and Fig. 3 is a side elevation of a 25 slightly modified form of the carry iron detached from the dead block and showing the same in reversed position in dot and dash lines.

My invention relates in general to a 30 draw-bar coupler support, and more particularly relates to a removable carry iron and its supporting buffer casting or dead block.

My invention has for its object to provide 35 an improved carry iron arrangement in which the iron may be dropped to a position, without becoming detached from the supporting parts, in order to permit the vertical lowering of the coupler and its 40 attached mechanism.

It is a further object to provide in a device of the above outlined character relatively broad flat bearing surfaces for the iron, and to so arrange the parts that the iron may be locked into position in a simple manner, and without multiplicity of structural parts.

I attain the above outlined objects, broadly, by constructing a dead block A with aligned 50 shelves and a carry iron B or B' insertible into said block by a transverse movement below the coupler C, in which position it is locked by means of pins D.

Described more in detail I have shown

the dead block A as consisting of a suitably 55 riveted face plate 4, fastened by means of the rivets 5 to the end sill or other suitable part of the car, and extending centrally and downwardly from the lower portion of the plate, and integral therewith is the open 60 bottom hood 6, terminating in depending brackets 6^a—6^b, affording a coupler opening 7 between said brackets in which is disposed the coupler C. The lower portion of each side wall of the hood 6 is formed into 65 an integral and outstanding hollow foot 8, the bottom of each of which feet form a shelf to support the carry iron B, herein-after more fully described. These feet are slightly different, and referring more particularly to the one disclosed in the left-hand side of Figs. 1 and 2, it will be noted that the shelf 9 is slotted or divided transversely so as to provide an opening 10 in the bottom thereof, which opening extends 70 from the outer wall of the foot through the inner wall outlining the coupler opening. The width of this opening 10 is substantially 75 one-half of the width of the recess 11, so as to provide a relatively broad shelf 9 on opposite sides thereof. Slightly above the shelf 9 the inner wall 12 of the hood has an opening 13 therein extending through the entire width of the recess 11, so as to 80 permit the insertion of the carry iron B. 85 The slot 14 in the other foot is substantially L-shape in vertical section, and is opened through the bottom through the transversely extending opening 15. This opening forms the head of the T-shaped opening 16, the stem of which opening is in alignment with the opening 10 and provides shelves 17, which shelves are substantially 90 in the same plane with and correspond to the shelves 9. 95

The carry iron B is shown to be a solid flanged bar, each end of which is formed integral with lateral projecting lugs 18 and 19. The lugs 18 are of a flat elliptical shape in transverse section and are of 190 greater width than height, so that when the carry iron is in the coupler supporting position shown in Fig. 1 the lugs 18 will rest on the shelves 9 and will fit within the angle formed by the top wall of the foot 8 195 and the shelves 9, and at the same time will afford a broad bearing surface between the carry iron and the shelves 9. The open-

ing 13 in the foot 8 is made merely of a height sufficient to permit the insertion of the lugs 18, and these lugs are of such height relative to the opening that when the iron is in the depending position shown in dot and dash lines in Fig. 1 the iron cannot be jolted out of the recess 11. The lugs 19 are of a conventional cylindrical form, and are preferably of this form so that the opening 15 may be made as small as possible, thereby affording relatively larger shelves 17. It will be understood that the carry iron B is preferably mounted in position by first introducing the lugs 18 through the opening 13 into the recess 11, permitting them to rest on the shelf 9 and then passing the lugs 19 through the opening 15 until they rest upon the shelf 17, and the iron is then slid transversely until the lugs 18 engage the angle in the pocket 11, and the iron is maintained in this position by pins 20, which pass through the aligned perforations in the top and bottom walls of the pocket containing the lugs 19 and engage these exteriorly of the said lugs, as said lugs rest on the shelves 17. The pins are fastened in position by any suitable means, such as the cotter pins 21. By this construction it will be seen that the holding pins 20 do not pass through the carry iron to weaken the same, as is common with some known structures of this character. The lugs 18 and 19 are disposed nearer one bearing face of the iron than the other, so that reversing the position, as shown in dot and dash line in Fig. 3, will adjust the coupler vertically so that it may assume one of two vertical positions.

What I claim is:

40. 1. A striking casting having a plurality of brackets provided with shelves spaced longitudinally and transversely relative to each other, a carry iron fitting between and supported on certain of said shelves so as to be pivotally movable toward operative position and having laterally extending integral lugs projecting from each end thereof serving as pivot supports on some of said spaced shelves, said casting having portions overhanging said lugs to prevent vertical movement of said iron.
55. 2. A striking casting having a plurality of shelves spaced longitudinally and transversely relative to each other, a carry iron fitting between and supported on certain of said shelves so as to be pivotally and slidably movable to operative position and having laterally extending integral lugs projecting from each end thereof resting on a plurality of said shelves, said casting having portions overhanging said lugs to prevent vertical movement of said iron, and a removable pin carried by the casting exteriorly of the iron to prevent transverse movement
60. 65. 70. 75. 80. 85. 90. 95. 100. 105. 110. 115. 120. 125. 130.

3. A striking casting having a shelf and a wall meeting to form an angle, said shelf having an opening therethrough, a carry iron adapted to swing into said opening and having lateral lugs supported by said shelf, and means maintaining one end of the iron in the angle.

4. A striking casting having transversely spaced recesses facing each other, in combination with a carry iron having integral laterally extending opposite end portions disposed in said recesses when in coupler supporting position, and a removable locking member exteriorly of the carry iron adapted to maintain said carry iron in supporting position, said carry iron being adapted to swing to inoperative position while it is supported at one end only.

5. A striking casting having spaced parallel shelves, a carry iron adapted to be supported in coupler supporting position on said shelves and to drop away from coupler supporting position, said carry iron having laterally extending lugs supported by said shelves, and walls connecting opposite ends of said shelves, the walls being adapted to restrict longitudinal movement of said carry iron in one direction.

6. The combination with a striking casting, of a carry iron having one end pivotally and slidably mounted in said striking casting, and a removable locking member adapted to extend into said striking casting in alignment with the opposite end of said carry iron.

7. The combination with a carry iron having integral transversely extending lugs formed near each of its ends, said carry iron being mounted in said striking casting and being pivotally movable to and from a vertical position, and insertible into said striking casting by a transverse movement.

8. In a device of the class described, a striking casting, provided with depending bifurcated portions each of which is provided with a recess, with two slots leading to one of said recesses, in combination with a carry iron mounted in one recess and adapted to be inserted in said recess through one of its slots, said carry iron being adapted to swing to inoperative position while it is supported at one end in but one of said recesses.

9. A striking casting having a shelf terminating in a stop at one end, said shelf having an opening therethrough, a carry iron adapted to be projected into said opening and having fixed lateral lugs near each of its ends, some of which are supported on said shelf and some of which are adapted to serve as supports for the opposite end of said carry iron, said carry iron being pivotally movable to and from operative position.

10. In a device of the character described,

- a carry iron formed of one piece and provided with fixed laterally projecting lugs extending from near each end thereof, in combination with a recessed striking casting 5 formed with recesses adapted to support opposite ends of the carry iron, and having passages leading to said recesses adapted to permit seating said carry iron therein, said carry iron being pivotally movable to and 10 from operative position.
11. In a device of the character described, a striking casting having one portion formed with a pocket formed with a stop at its outer end and another portion provided 15 with a pocket formed with a stop at its inner end, in combination with a carry iron provided with transversely extending integral lugs at either end, which lugs are insertible in said pockets.
12. In combination, a bifurcated striking casting having a vertical slot through each leg of the bifurcation and a coupler support provided with integral laterally extending lugs at each of its ends, said coupler 20 support being pivotally movable to and from operative position, adapted to be seat- 25
- ed in said striking casting by a longitudinal movement.
13. In combination, a bifurcated striking casting having a vertical slot through each leg of the bifurcation and a coupler support provided with integral laterally extending lugs at each of its ends and pivotally movable to inoperative position, said coupler support being adapted to be seated 30 in said striking casting by vertical and longitudinal movement of the support.
14. In combination, a bifurcated striking casting provided with slotted recesses in each leg of its bifurcated portion, in combination with a carry iron which is provided with integral lugs extending transversely near each end thereof and adapted to be pivotally and slidably movable to operative position in said striking casting. 35

In witness whereof I have hereunto set my hand in the presence of two witnesses.

PAUL BATEMAN.
